UNITED STATES PATENT OFFICE.

IRENEO ROMERO AND ANTONIO COSTINI, OF CALEXICO, CALIFORNIA.

FORM AND SECTION FOR BUILDING WALLS.

Application filed July 14, 1925. Serial No. 43,552.

This invention relates to improvements in building constructions, and forms and sections therefor.

The primary object of this invention is the provision of a relatively simple and economical slab or building form or section which may be assembled in connection with other similar forms or sections to construct the walls, roofs, or other parts of a building.

10 A further and important object of this invention is the provision of a novel type of building form or section, comprising a frame efficiently constructed to receive a mixture of cementitious material, such as

15 adobe.

A further object of this invention is the provision of a reinforced adobe building form or block or section, embodying a relatively simple and economical construction

20 whereby to utilize adobe or like mixture in practical manner for building constructions, whereby said building constructions may be economically produced and rendered fire-proof, sanitary, and resistant to heat and

25 cold.

A further object of this invention is the provision of a novel method of constructing building forms or sections and buildings thereof.

30 Other objects and advantages of this invention will be apparent during the course of the following detailed description.

In the accompanying drawings, forming a part of this specification, and wherein similar reference characters designate corresponding parts throughout the several views,

35 Figure 1 is a fragmentary outside elevation of part of a wall and part of the roof of a building construction, showing more particularly the novel features of the improved building form or section and relative assemblage to provide a durable building construction.

40 Figure 2 is a cross sectional view taken through the building construction substantially on the line 2—2 of Figure 1.

45 Figure 3 is an enlarged fragmentary cross sectional view taken substantially on the line 3—3 of Figure 1.

50 Figure 4 is a vertical sectional view taken thru the building construction form substantially on the line 4—4 of Figure 1.

55 Figures 5, 6 and 7 are fragmentary cross sectional views designating successive steps in the production of the form and its application to a building construction.

Figure 8 is a side elevation of a form or frame, showing the construction of the same.

Figure 9 is a cross sectional view taken substantially on the line 9—9 of Figure 1.

60 In the drawings, wherein for the purpose of illustration is shown a preferred embodiment of this invention, the letter A may designate the preferred type of building form, which may be used to produce a building construction consisting of walls C and a roof D; the roof D being preferably constructed of a somewhat different type of form E. In Figure 8 is shown a frame F, 65 of special construction, which may be used for producing one of the building walls; the same involving common characteristics with the frames of the forms A and E, as will be subsequently detailed.

70 Referring to the form A, the same preferably comprises an elongated frame-work 10, adapted to receive the adobe or cementitious material 11, and including a retaining and reinforcing arrangement 12 to so receive the material 11 as to provide a substantially 75 impervious and reinforced section or form, a plurality of which may be used to provide the walls of the building B.

75 The frame 10 of each section preferably comprises the uprights, side rails, bars or members 13 and 14, which may be of any desired length consistent with the number of hereinafter mentioned compartments which

80 it is desired to provide in each section. Cross bars or members 15 are provided at spaced 85 intervals between the rails or bars 13 and 14, secured in right angled relation thereto in any approved manner, and thus providing rectangular compartments or pockets 18 of any approved number, along each of the forms A. The uprights or bars 13 and 14 together with the cross bars 15 provide these compartments 18, which are preferably 12" x 18" in dimension, as this has been found

90 to be of best size in which to provide the sections. These bars 13, 14 and 15 are pref-

95 erably of lumber, in size 1" x 4", although for the lower walls of building constructions, this framework may be constructed of 1" by 6" lumber. The framework provided by 100 these bars may also be formed of steel, or metal, or other approved means, and the shape of the compartments may be polyg-

105 onal, round, or any other shape than rectangular, which is specifically shown in the drawings. It is to be noted that the cross bars 15 are of the same width as the side

bars or uprights 13 and 14, so that the outer edges of the bars 15 are flush with the outer edges of the bars 13 and 14, at both sides of the frame in order to provide the compartments 18.

The cementitious retaining and reinforcing construction 12 is provided for each compartment 18, being disposed entirely in the compartment, in countersunk relation inwardly of the flush outer edges of the framework so that adobe or cementitious material 11 will entirely cover and embed the reinforcing and retaining construction 12. This reinforcing 12 preferably includes the ribs or key flanges 19, which are secured in peripheral arrangement within the compartment 18 entirely about the inner periphery of these compartments or pockets 18; it being thus understood that the retaining flanges or key ribs 19 are secured to the inner surface of the side uprights 13 and 14, and to the compartment facing surfaces of the cross bars 15, in the relation shown in the drawings. The ribs or retaining pieces 19 are of course considerably less in width than the width of the framework bars, and are disposed substantially midway between the flush opposite outer edges of the framework which provides the compartments 18, so that the same are entirely disposed in the compartments inwardly of the flush opposite marginal edges of the framework. In addition to the retaining flanges or ribs 19, it is preferred to provide other bracing and retaining means in each compartment, and to this end the preferred arrangement is the provision of crossed diagonals 20 and 21, affixed in any approved manner at their ends in the corners of the framework; the said diagonals 20 and 21 being disposed at opposite sides of the plane formed by the retaining ribs or flanges 19, as is illustrated in the drawings; it being of course understood that the diagonal cross pieces 20 and 21 are relatively shallow, so that when in position in the compartments 18 they lie entirely within their respective compartments, in spaced relation inwardly of the outer marginal edges of the frame in which they are disposed, so that they may be entirely embedded in the cementitious material or adobe 11, as is illustrated in the drawings.

Retaining shanks 25 may extend inwardly of the compartment 18 from the facing edges of the retaining ribs or flanges 19, for more effectively retaining the cementitious material in place in the frame compartment, and these shanks 25 may in reality be extensions of the nails which secure the ribs or key flanges 19 in place. Similarly nails, wires, or other metallic parts 26 may be used upon the retaining pieces 20 and 21, midway secured in the pieces 20 and 21, and providing projecting shanks extending into

the compartments 18 at opposite sides of said cross retaining pieces 20 and 21, as is illustrated in the drawings, for further co-operation in holding the slab of adobe in place.

The sections may have the compartments thereof provided with any approved retaining arrangement, such as wire, dowels, tongues and grooves, cross pieces extending in different directions, and other means than that shown in the drawings; it being understood that in the preferred instance all of the retaining work is disposed in the compartment 18 so as to be entirely embedded in the adobe or cementitious material which is to be received in and to cover the sections A.

In Figure 8 has been illustrated a frame F, which includes parts similar to the frame F of the form or section A above described, and the same reference characters in so far as they are applicable have also been applied to the frame F. However, the frame F may have the compartments 18 thereof provided with different retaining constructions. Thus, for the upper compartment 18 of the frame F, the retaining means may consist of a vertical bar or retainer member 30, having the upper and lower ends thereof attached in any approved manner to the reduced ribs 19; the retaining member 30 preferably supporting the nails or elements 31 having the oppositely extending projections or shanks in the compartment 18 for the retention of the cementitious filling. The intermediate compartment 18 of the frame F may consist of the retaining construction 12 above defined. The lower compartment 18 illustrates a means consisting of a pair of vertical bars 33 and 34, secured at their upper and lower ends to the retaining ribs or flanges 19, at opposite sides of the plane of said flanges 19, in the lower compartment 18, and respectively supporting the opposite projecting pins, nails or shanks 35^a and 36^a, in the manner above described, for retaining of the adobe or cementitious filling material 11. The frame F may be used where it is desired to provide a more stable retaining means in one portion of the section than another, as in use in the portions of the well against which persons lean, or against which knocks most frequently come, to give the adobe material extra reinforcement, in particular compartments.

Another feature of the frames of the improved building forms or sections is the provision of tongue and groove connections between the adjacent sections, to hold them in place. Thus, at the exterior surface of one of the uprights of each frame, a tongue 35 may be provided, and inwardly of the exterior surface of the other upright 14 of each frame, a groove 37 may be longitudinally provided adapted to receive the tongue 13.

35 of an adjacent section. The tongue and groove connections are formed in special relation; the tongues 35 being deeper or wider than the depth of the grooves 35, so that 5 when the tongue of one section is in the groove of its adjacent section, a longitudinal fissure or groove 36 will be provided, at the juncture of the frame uprights or side bars, wherein the stucco or plaster may 10 anchor when the final coating is placed over the forms or sections of the assembled wall. These fissures or grooves 36 of course occur at both sides of the wall, as it is contemplated to provide plaster at the inside of the 15 wall and stucco at the exterior thereof; the fissures thus cooperating, with other means to be subsequently described in replacing lathing, conventionally used for holding plaster and stucco.

20 Referring to the manner of completing the sections by the filling in of the adobe or cementitious filler 11, it is preferred to provide the filler 11 of adobe, such as may be found in various sections of the country, or 25 may be found in the vicinity in which the building is to be erected. With this adobe, clay, or analogous material which may be rendered plastic and subsequently hardened, it is preferred to mix from twenty-five to 30 forty per cent of any of the following materials:—Sawdust, excelsior, straw, hay, or other material susceptible of acting as a 35 good binder with the cementitious materials used, to give it body, and render it durable and capable of considerable resistance which the adobe by itself does not possess.

As to the manner of constructing the sections, after the frames have been completed, they are laid around the base of the building 40 upon which the frames or sections are to be erected, preferably flat upon the ground, and in the position from which the sections will be raised, directly into the wall structure. While laying horizontal upon a platform or 45 upon the ground, the pockets or compartments 18 of the frames are filled with the cementitious material until flush with the opposite side edges of the frame. The outer surfaces of the adobe or cementitious material in each of the frame pockets, gravel, 50 stones, pebbles, or like material is partially embedded in the exterior surfaces of the frame, to give the said surfaces a rough appearance in which to anchor the final coating 55 of stucco or plaster adapted to be placed upon the walls. In lieu of so treating the exterior surface of the adobe cake in this manner, the same may be raked, or otherwise roughened.

60 After this preparation of the section, the cementitious filling, which is preferably adobe with a binder, is left to dry in the frame, either by natural or artificial means; it being of course understood that the frame 65 is sufficiently elevated so that an open space

occurs between the same and ground or platform for air circulation. As the mixture of adobe in each compartment slowly dries, the cake will be contracted, and when finally dried, the cake of adobe in each compartment will have been so contracted that fissures or spaces 40 are provided peripherally between the outer edges of the cake of adobe and the inner peripheries of the frame bars 70 13, 14 and 15, as is illustrated in the drawings, so that in each compartment these fissures 40 are provided peripherally about the compartment and are important for the purpose of anchoring the final plastering or stucco coating to be received at the inner 75 80 and outer surface of the wall, as the case may be.

Referring to the building construction B, the wall C is formed by vertically arranging the forms A in their tongue and groove connected arrangement, so as to provide the vertical fissures 36. As is illustrated in Figures 1 and 2, the walls are mounted upon sills, or floor constructions in any approved manner, and as is illustrated in Figure 1, 85 where a doorway or casements are to be provided, special casement framework 45 may be provided in cooperative relation with the forms or sections A, and these sections A are not restricted to a vertical positioning, 90 but may be horizontally positioned, as is illustrated above the doorway in Figure 1.

Somewhat special framework will have to be provided for the corner sections of the building construction, as is illustrated in Figure 9, where the abutting side rails of the corner frames have been designated by numeral 47, and are arranged at preferably a 45° angle to the planes of their respective frames; although they have the tongue and 100 groove and retaining arrangements as above 105 described for the form A.

The wall C after the nailing of the side rails 13 and 14 in their tongue and groove jointed relation, to provide studs, has been 110 effected, and after the same have been secured in rigid position between the floors of the building or the roof thereof, they are given an inside coating of plaster 48, and an exterior coating of stucco 49, which coatings 115 are effectively anchored in the fissures or crevices 36 and 40, and it is also to be noted that upon contraction of the adobe cakes 11, that they countersink slightly from the outer edges of the framework, to give the 120 coatings 48 and 49 additional anchorage for holding them in suspension.

The roof sections E are analogous in practically all instances to the framework 125 of the form A, and comprises the spaced longitudinal bars or rails 50, connected by cross bars or pieces 51, to provide the compartments 52 in each of the sections 53 of the roof D, wherein the adobe cake 54 may be formed, in similar manner as above 130 de-

scribed. Also, the same retaining construction may be provided for the roof sections E, as above described for the section A. As an additional feature of the framework of the sections E of the roof, the same are provided with floors 56, upon which the cakes of adobe rest, as is illustrated in Figure 2 of the drawings, and after the drying and contraction of the adobe cakes 52, the final roof coating 10 57, of any approved character may be placed. The roof section rails 50, of course, have approved anchorage on the walls of the building.

From the foregoing description of this invention it is apparent that a type of building section has been provided, which may be used for the formation of walls, roofs, and other parts of building constructions, and which because of its use of inexpensive materials, may be economically constructed, and when completed provides a fire-proof wall for building constructions. A wall or building construction of the novel sections is sanitary, and is resistant to the ordinary 20 loads, forces and stresses of building constructions. The building section is adaptable for a wide variety of uses in connection with cheap and expensive buildings. Building constructions of the sections may be 30 quickly formed, and are of a permanent and durable character, which is insulating both to heat and cold.

Various changes in the shape, size, and arrangement of parts may be made to the 25 form of invention herein shown and described, without departing from the spirit of the invention or the scope of the claims.

We claim:

1. In a frame for building sections, the 40 combination of a framework providing a compartment therein, narrow retaining ribs formed rigid with the framework extending into said compartment inwardly of the outer edges of said framework at opposite sides of the ribs, and a retaining brace extending across said compartment and disposed therein and affixed at its ends to said framework.

2. In a frame for building sections the 50 combination of a framework providing a compartment therein, retaining ribs formed rigid with the framework extending into said compartment inwardly of the outer edges of said framework at opposite sides of the ribs, a retaining brace extending across said compartment and disposed therein and affixed at its ends to said framework, and anchoring pin projections carried by the framework and retaining brace extending 60 into said compartment.

3. In a frame for building sections the 65 combination of a framework providing a compartment therein, retaining ribs formed rigid with the framework extending into

said compartment inwardly of the outer 65 edges of said framework at opposite sides of the ribs, a retaining brace extending across said compartment and disposed therein and affixed at its ends to said framework, anchoring pin projections carried by the framework and retaining brace extending into 70 said compartment, and cementitious hardened material disposed in the compartment of said framework and embedding the retaining ribs, brace, and anchor projections 75 therein.

4. As an article of manufacture a frame 80 for building forms comprising side and cross bars providing a compartment, and reduced retaining ribs peripherally arranged 85 interior of the compartment about said bars and inwardly of the outer edges of said bars at opposite sides of the ribs.

5. As an article of manufacture a frame 90 for building forms comprising side and cross bars providing a compartment, reduced retaining ribs peripherally arranged 95 interior of the compartment about said bars and inwardly of the outer edges of said bars at opposite sides of the ribs, and cross braces diagonally extending across the compartment and entirely disposed therein.

6. As an article of manufacture a frame 100 for building forms comprising side and cross bars providing a compartment, reduced retaining ribs peripherally arranged 105 interior of the compartment about said bars and inwardly of the outer edges of said bars, cross braces diagonally extending across the compartment and disposed therein, and a hardened cementitious cake in said compartment embedding the retaining ribs and 110 cross braces therein.

7. In a building frame the combination of 115 framework open at opposite sides providing a compartment with a reduced retaining flange peripherally extending entirely about the interior of said compartment, retaining means connected at its ends to said frame and extending across said compartment and disposed entirely therein, and adobe held by the retaining means and retaining flange in 120 said compartment.

8. In a wall construction the combination 125 of a plurality of building sections, tongue and groove means for connecting said sections in slightly spaced relation to provide crevices, and a cementitious coating exteriorly on said sections having anchor portions extending into said crevices.

9. In a building construction a wall 130 formed of a plurality of sections, tongue and groove means for connecting said sections in slightly spaced relation to provide crevices between adjacent sections, each of said sections including compartments, cementitious cakes for the compartments, means retaining the cementitious cakes in said com-

partments, and cementitious coatings exteriorly on the sections anchored in said crevices.

10. In a building construction a plurality of sections, means connecting the sections in slightly spaced relation to provide crevices therebetween extending longitudinally along the building construction, and a cementitious coating for said sections including anchor portions extending into said crevices longitudinally therealong, each of said sections including a frame having a compartment with cementitious filling in said compartment.

15. 11. In a building construction, building sections comprising compartments, cementitious cakes in said compartments, means retaining the cakes in said compartments in a slightly spaced relation to provide crevices, and a cementitious coating for the building construction including anchoring portions in said crevices.

12. In a building construction the combination of sections including frames having compartments therein, cementitious filling cakes in said compartments, means supporting the cakes in said compartments in slightly spaced relation to the frames to provide crevices, and a cementitious coating for said sections having portions of the coating material anchored in said crevices.

13. In a building construction a plurality of sections, means assembling the sections in spaced relation to provide longitudinal crevices along the building construction, each of said sections including a frame with compartments therein, filler cakes in said compartments, means retaining the filler cakes in said compartments in slightly spaced relation with said frames, and a cementitious coating over said building construction sections having portions thereof extending into and anchoring in the crevices between said sections and in the crevices of said sections

between the frames and cakes in the compartments thereof.

14. A roof for buildings comprising longitudinally extending supporting sections each including a framework with a substantially imperforate supporting floor providing pockets open at the side of the framework opposite the floor, cementitious blocks in said pockets, and a coating over said sections embedding said cementitious blocks therebelow.

15. A building construction comprising vertical sections each including upright rails connected by a plurality of cross pieces to provide a series of compartments, tongue and groove means connecting the side rails of adjacent sections in slightly spaced crevice forming relation, filler cakes retained in said compartments of the sections, means formed on the filler cakes to provide an anchor, and a coating over said sections anchoring on said filler cake and in the crevices between said sections.

16. As an article of manufacture a building section comprising a framework of side and top and bottom pieces defining a rectangular shaped compartment therein, reduced retaining ribs rigid with the side and top and bottom pieces extending into said compartment in a plane placed inwardly from the planes of the outer edges of the framework, diagonally extending cross braces secured at their ends in the corners of the framework and extending in X-shaped relation across the compartment and being disposed entirely within the frame inwardly of the planes of the outer edges of the framework, anchor means carried by the ribs and cross bars projecting into the compartment, and a cementitious filler in the compartment entirely embedding the ribs, cross pieces, and anchor means therein.

IRENEO ROMERO.
ANTONIO COSTINI.
